UNITED STATES PATENT OFFICE.

ROBERT W. SCOTT, OF BOSTON, MASSACHUSETTS, ASSIGNOR TO SCOTT & WILLIAMS, INCORPORATED, OF BOSTON, MASSACHUSETTS, A CORPORATION OF MASSACHUSETTS.

PATTERN MECHANISM FOR KNITTING-MACHINES.

1,225,683.

Specification of Letters Patent. Patented May 8, 1917.

Application filed July 25, 1913. Serial No. 781,052.

To all whom it may concern:

Be it known that I, ROBERT W. SCOTT, a citizen of the United States, and a resident of Boston, in the county of Suffolk and State 5 of Massachusetts, have invented a certain new and useful Improvement in Pattern Mechanism for Knitting-Machines of which the following is a specification.

My invention relates to means for automatically controlling the devices of a machine, which may, for instance, be a circular independent needle stocking knitting machine.

An object of my invention is to provide 15 an automatic pattern mechanism capable of an unusually large number of functioning movements in one cycle or repeat of the functional activities of the machine.

Another object is to provide an intermittently actuated pattern surface for a knitting machine which shall be capable of actuation at times and at a rate independent of the times and rates of actuation of the devices for the normal actuation of said 25 surface.

In the accompanying drawings,

Figure 1 is a left hand side elevation of so much of the frame and mechanical movement of a knitting machine as is necessary to 30 an understanding of my invention;

Fig. 2 is a front elevation partly in section on the line 2—2 of Fig. 1, of the driving and control elements of the said machine;

Fig. 3 is a development of the cam ring or cylinder of a knitting machine illustrating one type of knitting cams and needle controlling device with which the mechanism of my present invention may be usefully employed;

Fig. 4 is a detail plan partly in section above the bed plate of the head of a knitting machine having the devices illustrated in Figs. 2 and 3, showing the relation of the 45 needle controlling devices to the connections from the pattern mechanism;

Fig. 5 is a detail side elevation showing the mounting for the supplemental cams and parts of the connection to the pattern devices;

Fig. 6 is a vertical section on the line 6—6 of Fig. 2;

Fig. 7 is a diagram illustrating one relation of the auxiliary racking cam to the knitting cylinder and the needles therein.

As usually constructed, circular stocking knitting machines, when of the independent needle type employing latch or beard needles held to move in grooves on the surface of a needle-cylinder, are designed to 60 cause the co-operation of the needles, the web-holders, if employed, and a yarn guide or guides for feeding yarn to the needles, upon the rotation either of the needle cylinder with respect to a cam carrier equipped 65 with cams for giving the needles longitudinal movements, or upon the rotation of the cam carrier with respect to the needle cylinder, the rotary movement in either event producing a tube of knit fabric which may 70 be locally widened or narrowed for instance to form heel and toe pockets for a stocking, by back and forth movements of the rotary element of the knitting couple or head, and co-operating needle controlling devices. 75

A stocking knitting machine, if wholly automatic, may comprise such means and means for predetermining the extent of the rotary operation of the knitting head; means to predetermine the shift of the movement 80 of the knitting head from rotation to oscillation (including preferably means to alter the speed of the machine at or before such change); means to determine the placing out 85 of action of the needles which do not partake of the knitting of the pocket for the heel or toe; means for knitting a heel by first narrowing by placing some of the remaining needles out of action successively; means for widening by returning 90 certain of the needles to action; means for thereafter resuming circular knitting for a predetermined number of courses; or extent of fabric for the foot; means to repeat narrowing and widening operations 95 in the same order as for the heel to produce a toe, and means for thereafter stopping the machine or casting the fabric from the needles, or beginning the circular operation again for the leg of another stocking attached to the toe of the one just knit. For many purposes these operations may be accompanied in a predetermined order by alteration in the length of the loops knit and by changes at predetermined times of 100 the yarn supplied, and by such auxiliary activities as the adjustment of the tension upon the yarn, the adjustment of the tension upon the forming web, the local alteration of the stitch length, or the local splicing of 105

the fabric by the addition of another yarn, it may be for only a part of the circle of needles. Other operations may be automatically performed, at the proper time to cause 5 their effect at the proper place in the article of manufacture, as will be apparent presently.

I have chosen to illustrate my present devices in connection with a machine having 10 devices for reaching all of the above functions, but I have shown only so much of said machine as is necessary to the full disclosure of my present new devices, the said machine being of the type shown and 15 claimed in my Letters Patent No. 1,152,850 dated Sept. 7, 1915, and No. 1,148,055 dated July 27, 1915, but it will be understood that 20 my present devices are applicable to any automatic knitting machine having a driven pattern surface.

The needle cylinder 260, gears 30, 31, main shaft 32 mounted on a suitable bed D and frame A, B, and the means 49, 65, 61, 70 for oscillating sector 75, gear 35 and main shaft 25 32 may be of my patented or any usual construction, the machine also comprising the pattern shaft 80 actuated at times to cause cams fixed upon it to coact with the control devices, including the belt shipper 100 and 30 clutch shifter 92, to stop or change the speed of the machine and to change the motion of the knitting head from rotation to oscillation.

For the former purpose the cam disk 102 35 having suitable cams 104 acts upon a lug 114 on the belt shipper slide 100, held against the face of said cam disk by a spring 110.

The cam drum 90 fixed on the shaft 80 40 carries cams which coact with the follower 89 on the slide 92, to shift the clutch collar 33.

The sector 75 carries a crank arm 78 slotted 45 to receive for adjustment a crank pin 77 for a reciprocating actuator, such as the pawl 82, coöperating with a rack wheel 81 fast on the shaft 80. Said sector also carries crank pin 88 for a pawl 87 taking into the teeth of the ratchet 86 free on the shaft 80, which 50 ratchet 86 is attached to and operates a primary pattern surface, shown as a sprocket 84 carrying a mutable link endless pattern chain 85. Journaled on the rod 93 fast to the frame B is a pawl controller 83 having 55 a chain-reading lug 83^a, and an integral attachment 83^c standing between the faces of the drum 90 and the rack wheel 81. Said pawl controller attachment 83^c determines by its positions under the influence of spring 60 84 and lugs 852, 853, etc., of different heights on the right-hand faces of certain links of said pattern chain, the extent of the engagement of the active toe of pawl 82 with the rack wheel 81.

65 Said rack wheel is provided with teeth of

a predetermined and irregular pitch in such an order as to enable the pawl 82 to find a tooth at or after the beginning of its constant but adjustable stroke as determined by the position of the pawl controller attachment 83^c, the effective length of stroke thus being under the control of the lugs 851, 852, etc., upon the pattern chain. It will be seen 70 that the wheel 81 will be operative if regularly cut, for instance if provided with forty-six regularly spaced teeth, but I prefer to provide long teeth angularly spaced upon said shaft 80 to bring them opposite the pawl in relation to the angular positions of the parts of the various cams necessarily given a long movement, to prevent the possibility of leaving the cam shaft in an improper position. The clutch shifting cams on the drum 90, for instance, and the associated mechanism for controlling the heel 85 and toe knitting devices, require such a comparatively large angular movement of the shaft 80, and long teeth 81^a and 81^b are provided on the wheel 81 for moving the pattern shaft and appurtenances respectively at 90 the beginning of the heel and the beginning of the foot. Long teeth 81^c and 81^d similarly represent the beginning of the toe and the end thereof. The rate at which the shaft 80 moves under the influence of the pawl 82 95 is a constant rate of one advance for each revolution of the crank shaft 55 and complete oscillation of the sector 75.

The shaft 80 thus controls or determines directly the times of the various operations 100 performed by the machine. The pattern chain 85 determines when any movement of said shaft shall take place, while the rack wheel 81 in coöperation with the lugs of the pattern chain and pawl controller determines 105 the extent of such movement. It is evident that the cycle of operations is repeated after one complete revolution of said cam shaft 80.

Certain of the various agencies at the 110 knitting head coacting with the movable element thereof to actuate the needles to knit may be adjusted at predetermined times by a main pattern surface deriving its motions from the cam shaft 80. Said shaft 115 projects at the left hand side as shown in Figs. 1 and 2 to receive the gear 122 fixedly mounted on said shaft, for instance by a pin 200 through bores in an elongated hub 201 and said shaft. Said gear 122 meshes 120 with the gear 123 journaled on a stud 124 projecting from the left frame B, which gear in turn meshes with the gear 121, similar to the gear 122, which is attached to a cam drum 120 journaled on the projecting end 125 of the sector shaft 76.

Cams removably attached to the surface of said pattern drum constitute a movable pattern surface arranged to contact with and actuate members of a series of thrust 130

bars 460 guided at their lower ends in a comb 451 attached to a stud 450 parallel with the shaft 76 projecting from the end frame B, which thrust bars at their upper ends engage the instrumentalities coöperating with the needles for effecting changes in the knitting, such for instance as the yarn changing yarn guides, a yarn clamp and cutter, a yarn take-up device, a device for closing the yarn-feed-lever gap in the latch ring, and devices for locally altering the length of the stitch and for splicing a section of the knit tube. Said constructions may be the same as those in my said patents.

15 Cams on drum 120 may also be employed to coat at the proper times with adjustable plungers 283 carried by a two-armed lever 281 journaled on the stud 450, one arm of said lever taking under a lug on a tubular 20 column 280 upon which a rotary support or supports for the needle cylinder may find a bearing, in order to automatically adjust the length of the stitch, by elevating or lowering the needle cylinder with respect to 25 the vertically fixed cam ring.

Cams on said drum 120 may also be employed to coöperate with the lever 215 journaled on the stud 124 to lift the rod 216 to operate some of the instruments concerned 30 with the knitting function, for instance to control a switch cam for lifting the needles rendered idle when knitting the heel and toe, and for operating the widening picker, to determine when it shall be active.

35 It will be understood that the pattern cams on the pattern surface of the drum 120 and their operated connections, as above suggested, are merely typical of automatically adjustable knitting devices, which may well 40 be those of the prior art, and that I have illustrated the drum 120 and the reading or indicator members 460, 283 and 215 merely as instances of devices which might be replaced by any usual or known arrangement for automatically operating the knitting devices proper. It will be clear, how-

ever, that the times at and extent to which the various devices reached by said connections will be moved will be determined by 50 the movements of the shaft 80, transmitted to said drum 120 through the gearing 122, 122, and 121, and that the points in the fabric at which the changes caused by indications on said drum 120 occur will be determined in the first instance by the position of the lugs 852, 853, etc., on the primary pattern surface or pattern chain 85.

The pattern chain 85 may be of any necessary length and supported in any manner 60 known in the art, but whatever particular device is employed for this purpose will permit alteration of the said chain, as by removing and replacing links, to enable the adjustment of position in the fabric of the 65 knit structures controlled by the pattern

surface of the drum 120, and also with respect to the time in the operation of the changes controlled by the drum 90 and the cam 102.

When it is desired to perform any special 70 or unusual operation upon the machine, to be repeated, for instance at least once in each complete article made, it will with the described connections be necessary to provide upon the drum 120 a cam to move one 75 of the described connections, for instance one of the thrust bars 460, at a time corresponding to the desired place in the fabric, and in a manner to coöperate with the special instrumentality to cause it to perform 80 its operative cycle. But, referring now to Fig. 6, it will be apparent that the necessary operations of the machine consume a large part of the one revolution of the shaft 80 which may be devoted to a single article, 85 the operations for instance of knitting the heel, foot and toe of a stocking ordinarily corresponding to over half the surface of the drum, requiring all of the teeth between 81^a and 81^b, and a corresponding movement 90 of the drum 120. Into the remainder of the surface of the drum, if a stocking is to be knit, must be crowded all of the indications for special operations intervening between the toe of one stocking and the heel 95 of the next stocking. A special operation requiring a segment of the drum surface corresponding in extent to one of the teeth 81^a, 81^b, etc., may usually be provided for only by shortening the movement of the drum 100 devoted to other purposes occurring during the same interval, thus increasing the required accuracy of the parts, and when the special operation attempted to be carried out upon the machine necessitates any accurate positioning, for instance as of special 105 needle cams, with respect to the moving needle cylinder, reliance upon indications moving with the shaft 80 may limit or prevent the use of the machine for all of the 110 desired purposes.

It is mechanically desirable to drive the drum 120, the shaft 80 and its attachments at a comparatively slow rate. In the instance shown in the drawings such rate is 115 provided for by the described construction in which the actuator for the shaft 80 is the pawl 82, which makes one forward motion during each revolution of the gears 60 and 65 and the shaft 55, which gears 120 and shaft rotate at a reduced rate with respect to the shaft 32 and the knitting head; for instance, when the belt is on the pulley p^2 , and shaft 55 is driven through pinion 49 and gear 65, which is the normal 125 condition during rotary knitting. The gear 60, if the proportions are as shown, will then make one revolution for every four revolutions of said pulley; while if the belt is upon the pulley p' and the drive is 130

through the pinion 38 and the clutch collar 33 and thence to the knitting head (which is the condition for reciprocatory work) said gear 60 may make one revolution for 5 every three revolutions of said pulley p' . But the relation of the gear 60 and the pinion 38 remaining unchanged, the pawl 82, when the gearing is of the proportions instanced, will make its forward stroke during substantially two revolutions of the shaft 32 and the knitting head.

It will be seen that a control device or pattern mechanism operatively connected to any of the instrumentalities in a machine 15 such as above indicated, or containing knitting devices of a related character, will necessarily be associated with a positioning mechanism such as the said shaft 80, in order broadly to determine the time at 20 which the changes to be effected in the knitting will take place. This association, when it is a rigid connection, produces the difficulties above mentioned as mere instances of others which will be apparent 25 to those skilled in the art. By my present invention I have provided, while retaining the shaft 80 and means associated with it for determining the time at which the operations will take place, a special type of 30 pattern drum, or surface, so mounted that it may be moved when the shaft 80 and its connecting train of mechanism is at rest and still capable of being actuated by said shaft to bring it into time with the 35 remaining indications.

As one instance merely, I will now describe the construction and operations of said auxiliary surface and the connections from it when employed for operating special cams for making drop stitch barriers, 40 or stop structures, starting selvages and out-turned welts. In my said Letters Patent No. 1,148,055, I have described and claimed needle controlling devices useful for these 45 purposes, said devices comprising in one form the special cams and knitting cams illustrated in Fig. 3 of this application, including symmetrically paired stitch cams 6 and 7 having needle retracting slopes 50 coöoperating with the butts of the needles n' and n^2 to give them their stitch-forming movement, needle advancing slopes 6^a and 7^a to elevate the needles to cause them to clear their latches, in coöperation with a 55 top center cam 8 to carry needles advanced by one of said inclines 6^a or 7^a beneath the following stitch cam 6 or 7, and the bottom center cam 9 coöoperating with said top center cam 8, and so placed as to provide 60 an idle groove 10 too low to permit needles entering it to contact with the yarn supplied by yarn guides (not shown) at the region of the cam 8.

The above structures coöperate with a 65 cam ring 271 providing a cut-away portion

having cam slopes 5, 5 in which the stitch cams are operatively positioned; an upper ledge 4 at the level of which the needle butts travel, between their successive activations, in a position in which the loops are 70 not cleared beneath their latches, a cut-away portion 11 and a cam groove 365 for coöperation with the butts of needle actuating jacks 380, 381 operating in the same grooves as the knitting needles.

For the purposes above suggested, the said machine is also equipped with supplemental cams 382 and 2, constituting needle controlling devices, which cams are held to slide substantially radially with respect to the needle cylinder in grooved standards 490 and 18 forming part of the bracket 19 attached to the bed plate D of the knitting head as by screws 22.

The normal position for said cams 382 85 and 2 is one of retraction under the influence respectively of the springs 14 and 17 in bores in the said standards 490 and 18, plungers 13 and 16 respectively in said bores taking against the down-turned outer ends 90 12 and 15 of the said respective cams 382 and 2. It is necessary to carry out all the operations for making starting selvages, welts and drop stitch barriers to move the said cams 382 and 2 at predetermined times 95 to at least two positions of adjustment in advance of their outward position of rest. In the case of the cam 2 it is desirable to move said cam at predetermined times to three positions in advance of its position of 100 rest.

In the case of each of said cams it is desirable to move said cams with accuracy to said adjusted positions during the passage of a particular segment of the needle cylinder, or 105 during the passage of a given point upon said needle cylinder through a predetermined angle of movement. Such adjustments of the cams 382 and 2 are broadly for the purpose of securing their first contact in 110 their respective adjusted positions with particular needles of the segment of needles moving past said cams, for instance, of the first of the usual series of high butt needles n' following the usual series of low butt needles n^2 .

It will be understood that I have illustrated the knitting mechanism employing the cams 382 and 2 merely as an instance of devices with which my new pattern devices 120 are particularly useful, and that said devices are well adapted to the control of other ancillary parts requiring to be moved in a simple or complex order at predetermined times in coöordination with the automatic 125 movements of a knitting machine of the illustrated or any known type.

On the left end of the pattern shaft 80, and journaled on the elongated hub 201 of the gear 122, I provide the auxiliary pattern 130

surface, conveniently made as a drum 220 on the surface of which the cams 221 may be removably mounted.

Driving movements with the shaft 80 are given the drum 220 by a dog 222 projecting from a collar 223 fastened on the outer end of the shaft 80, as for instance by the set screw 224. The dog 222 encounters a lug 225 on the inner surface of the drum 220.

The drum 220 will thus partake of the motions of the shaft 80 whenever the dog 222 contacts with the lug 225. So far as described the surface of the drum 220 is available for cams to be used for the timely actuation of the indicator levers or adjusting connections, with such advantage as will accrue from the provision of an additional surface for pattern cams, such as those on the drum 120.

The drive connection 222, 225 for the drum 220 is unidirectional, permitting the drum 220 to be moved by an exterior operating means with respect to its bearing on the shaft 80. I may thus utilize the said drive connection 222, 225 for said drum to position the said drum in coördination with remaining indications of the system made up of the shaft 80 and its attachments and the drum 120, but at the same time provide for the independent actuation of such devices as are controlled by said drum 220.

To this end I form integrally with the drum 220 a ratchet 226 for coöperation with a pawl 227 carried by one arm of a two armed lever 228, journaled on the rod 93, which lever is given a rocking movement with respect to the rod 93 as a center by the cam 430 fastened on the main shaft 32 near the gear 31. The lever 228 is kept against the surface of the cam 430 by a spring 229.

The active toe of the pawl 227 is normally forced into contact with the ratchet 226 by a light spring 230 seated in shallow bores in said pawl and in a lug 231 projecting from the lever 228. Said pawl is pivoted at 232 and is provided with a projection behind the pivot carrying a pin 233.

The arc swept by the pivot 232 and the pawl 227 is comparatively short, and the travel of the pin 233 normally takes place in engagement with the under side of a pawl controlling arm 235 of a lever 236 projecting through an opening *b* in the frame B which lever is journaled inside of the frames of the machine on an internal projection of the stud 124, and is under the stress of comparatively strong spring 237. In this position the active toe of the pawl 227 does not engage the ratchet 226. Said pawl, however, may be dropped into engagement with the ratchet at predetermined times by the intervention of a lug 854 on the left hand side of a link or links of the pattern chain 85, which lug coacts with a chain reading lug 238 on said lever 236.

It will be evident that the drum 220 will be kept in time with the remaining agencies of the machine by the coaction of the dog 222 and the lug 225; and that upon the intervention of one of the lugs 854 on the primary pattern surface or pattern chain 85, the said drum 220 will be moved forward by its ratchet 226 and pawl 227 during such a time as is represented by the length of the lug 854. A spring brake 219 bearing 75 against the face of the ratchet 226 prevents over-throw of the drum 220 or its movement by friction of the gear 122 or hub 201.

If the dimensions are as shown in the drawings, the lug 854 may be retained under the chain reading lug 238 between successive forward movements of the ratchet 86 under the impulse of the pawl 87, which forward movements may take place during every fourth revolution of the knitting head. The drum 220 may thus be actuated during three revolutions of the knitting head, at such an intermittent rate as will result from the configuration of the cam 430. The said cam 430, see Fig. 7, may, for the special purpose of actuating the supplemental cams 382 and 2 be placed with respect to the shaft 32 so as to bring the active stroke of the pawl 227 at a time related to the passage by a particular segment of the 95 needle butts of the supplemental cams 382 and 2.

In common with the usual construction of stocking knitting machines, my machine may be equipped with a series of long butt needles *n'* and a series of short butt needles *n''*, each occupying virtually one half of the needle cylinder, and I may construct the cam 430 so as to provide two active surfaces, corresponding to active movements of the 100 pawl 227, and two concentric or idle surfaces, and a recovery incline connecting the parts of greatest and least radius, and I may so place the cam 430 with respect to the shaft 32 as to relate the active periods of 110 the pawl 227 to the passage of the particular parts of the needles past the cams moved by the pattern surface on the drum 220. For instance, I have indicated by the diagram Fig. 7 a cam 430 provided with an active or increasing segment 430^a, so placed on the shaft 32 as to cause its motion past the lever 228 during the passage of the middle of the short butt needles *n''* at the cams 382 and 2; a following concentric portion 120 430^b corresponding to the location of the following end of the short butt needles *n''* and the leading end of the long butt needles *n'*; an increasing segment 430^c corresponding to the angular position of the middle 125 of the long butt needles, and a recovery incline 430^d corresponding to the last of the series of the long butt needles.

It will be seen that the drum 220 may not only be actuated during the idle or recovery 130

stroke of the pawl 82, but that the movements of the drum 220 under the impulse of the pawl 227 may be brought into a rigid time relation with the passage of the particular needles desired to be first actuated with respect to the needle cams intended to actuate them. One cycle of operations to be carried out on the devices shown in Fig. 3 may, for instance, call for the positioning 5 of the cam 382 to first encounter the leading long butt needles; then positioning said cam during the passage of the long butt needles to encounter all the needles; and thereafter positioning the cam 2 so as to cause an advancing cam portion thereof to encounter the leading long butt needles, and thereafter to cause said cams 382 and 2 to retire during the passage of the long butt needles. Such an operation obviously could not be 10 performed by the pawl 82 and cams carried by the drum 120, without actuating the drum through the maximum stroke permitted by the pawl 82, and only in that event by the provision of accurate cam structures. 15 With the described devices pattern drum 220 may be moved forward by the incline 430^a of the cam 430 while the long butts are passing one of the operated needle cams; may then be held stationary during the 20 passage of the leading long butts by the concentric portion 430^b; and may then be advanced by the incline 430^c, without having necessitated any period for recovery of the pawl 227 to take a new tooth, which will not 25 take place till the passage of the recovery incline 430^d. I may thus provide on the drum 220 cams capable of coöperating with connections to such needle cams as 382 and 2 without any necessity for great accuracy 30 in their angular position with respect to the face of the drum.

As instances merely of connections capable of coöperating with such cams as the supplemental needle cams 382 and 2, I have 45 shown indicator levers 250 and 251 journaled on the end of the rod 93, said levers having broadened ends standing under drop rods 252 and 253 freely passing through bores in the table D, and in a bracket 254 50 attached to the left frame B. The upper ends of the said drop rods 252 and 253 may carry inclines 254 and 255 integral with collars 256, 257 adjustably held by set-screws on said rods. The inclines 254 and 55 255 respectively take against the down-turned ends 12 and 15 of the cams 382 and 2. The movements of the respective indicator levers 250 and 251 will thus be translated into radial movements of the respective 60 cams 382 and 2, as will be apparent from an inspection of Figs. 4 and 5.

Although I have described the operation of such cams as the supplemental cams 382 and 2 by the connections leading from the 65 drum 220 it will be obvious that the drum

220 may be utilized for the performance of many operations in connection with a knitting or other textile machine, or in any situation requiring a pattern device to be actuated at predetermined times related to the general activities of an automatic machine, but for any reason inconvenient to reach by means of the main directing cam, or pattern mechanism controlling said activities. In the instance illustrated the difficulty overcome by the use of the drum 220 is one flowing from the infrequency with which intermittent movements are given to the main controlling mechanism, and it will be seen that my improved devices enable me to avoid the expedites of providing a larger pattern surface, or of moving it more frequently. 70 75

While I have shown the drum 220 and its driving means in use in a machine having other pattern surfaces, it will be understood that my invention contemplates a pattern surface such as the drum 220 in use with a timing or pattern shaft such as the shaft 80, whether or not said mechanism may be combined with other pattern devices, such as the drum 120 herein disclosed. For instance, the device of the shaft 80 and the drum 220, and the connections from said drum and said shaft is obviously of use to obtain the proper timing of needle controlling devices in a 90 machine organized for comparatively few and simple changes between recurrences of the same structure, or one repeat of the pattern being knit. 95

What I claim is:—

1. In a pattern mechanism, a timing or pattern shaft, a primary pattern surface, and a pattern surface normally moved by said shaft, means controlled by said primary pattern surface to move said pattern shaft intermittently, in combination with devices independently controlled by said primary pattern surface for advancing said pattern surface with respect to said shaft at predetermined times. 100 105

2. A knitting machine having a rotary knitting element, needles, and needle controlling devices, an intermittently actuated timing or pattern shaft, a pattern surface normally moved by said shaft, and connections from said surface to said controlling devices, in combination with devices for advancing said pattern surface with respect to said shaft at predetermined times during a predetermined part of a revolution of said 110 115 120 rotary element only.

3. A knitting machine having a rotary knitting element, needles, and needle controlling devices, an intermittently actuated timing or pattern shaft, a pattern surface normally moved by said shaft, and connections from said surface to said controlling devices, in combination with devices for advancing said pattern surface with respect to said shaft at predetermined times during 125 130

a predetermined part of a revolution of said rotary element only, and means for holding said surface stationary during subsequent movement of said shaft.

5. A knitting machine having a series of needles, cams, and needle controlling devices relatively movable for knitting, a pattern mechanism, a timing or pattern shaft, a primary pattern surface and a pattern surface normally moved by said shaft and connections thereto for controlling said needle-controlling devices, in combination with means controlled by said primary pattern surface to move said pattern shaft intermittently, and devices independently controlled by said primary pattern surface for advancing said pattern surface with respect to said shaft at predetermined times during passage of a predetermined part of said series of 20 needles by said controlling devices.

15. A knitting machine having a circle of needles, knitting cams and needle controlling devices relatively movable with respect to the needles for knitting, a pattern mechanism, a timing or pattern shaft, a primary pattern surface and a pattern surface normally moved by said shaft, means controlled by said primary pattern surface to move said pattern shaft at predetermined times at intervals beginning 25 at relatively infrequent intervals, in a combination with devices controlled by said primary pattern surface for advancing said pattern surface with respect to said shaft at predetermined times at intervals beginning 30 and ending during the passage of a predetermined segment of the needles by certain of said controlling devices.

20. A pattern mechanism comprising a timing or pattern shaft, a primary pattern surface, and a main pattern surface moved by said shaft, means controlled by said primary pattern surface to move said pattern shaft at predetermined times, an auxiliary pattern surface and means to cause said auxiliary 45 surface normally to move coördinately with said shaft, in combination with devices controlled by said primary pattern surface for advancing said auxiliary pattern surface with respect to said means at predetermined times.

50. A knitting machine having a rotary knitting element, a timing or pattern shaft, a primary pattern surface, and a main pattern surface moved by said shaft, means controlled by said primary pattern surface to move said pattern shaft intermittently, an auxiliary pattern surface and means to cause said auxiliary surface normally to move coördinately with said shaft, in a 55 combination with devices controlled by said primary pattern surface for advancing said pattern surface intermittently with respect to said means at predetermined times related to predetermined parts of a revolution 60 of said knitting element.

6. In a knitting machine, knitting elements and means for predetermining the operation of said elements comprising a plurality of pattern surfaces and connections to certain of said elements comprising 70 groups of connections each positioned by a different one of said surfaces, in combination with advancing means for each of said surfaces, a primary pattern surface, and means operated by said primary surface for 75 independently determining the advance together in unison or the advance separately at different rates of each of said plurality of pattern surfaces.

7. In a knitting machine, a pattern or 80 cam shaft, a main pattern surface and means for moving it in unison with said shaft, an auxiliary pattern surface loosely mounted on said shaft and means on said shaft to encounter and drive said auxiliary pattern 85 surface, an independent actuating device for said auxiliary pattern surface, a primary pattern surface, and independent means each having an element on said primary pattern surface to independently control the actuation 90 of said cam shaft and of said auxiliary pattern surface.

8. In a knitting machine, knitting devices, a primary driving element, a main shaft, and means connecting said main shaft 95 to a driven element of the knitting devices, a severable connection between said primary driving element and said main shaft, a timing or pattern shaft, means having an element on said shaft for making and breaking 100 the connection between said driving element and said main shaft, means for intermittently advancing said pattern shaft, a drum having a pattern surface movable with said pattern shaft, and connections from said 105 drum to a part of said knitting devices, means on said pattern shaft for positioning said drum, means for driving said drum from said main shaft, a primary pattern surface and driving means therefor, and a 110 connection from said primary surface to said driving means for causing said means for driving said drum to be active and inactive at predetermined times.

9. In a knitting machine, knitting devices including a rotary element and driving means therefor, needle controlling devices, a primary pattern surface and means for driving said surface, means including a main pattern surface, operating means therefor 115 controlled by said primary pattern surface for determining the times and duration of the movement of said knitting devices, an auxiliary pattern mechanism comprising a pattern surface and means coöperating 120 therewith for positioning said needle controlling devices, means actuated by the said driving means to intermittently advance said auxiliary surface through a plurality of 125 steps in each revolution of said rotary ele- 130

- ment, and means having a part in contact with said primary pattern surface for rendering said auxiliary pattern advancing means active or inactive.
- 5 12. An independent needle knitting machine having needles and needle controlling devices, and means for operating said devices comprising a pattern surface, and a ratchet mechanism for moving said pattern
- 10 surface comprising a pawl, a cam rotating in time with a knitting element for advancing said pawl, said cam having active segments separated by dwells or idle segments, whereby the pattern surface may be ad-
- 15 vanced or held stationary in unison with relative movement of the needles and needle controlling elements of said machine through a predetermined angle of rotation.
13. In a pattern mechanism for knitting machines a primary pattern surface, a pattern surface and means for normally ad-
- 20

vancing said last mentioned surface under control of said primary surface, a ratchet mechanism independent of said means for advancing said surface comprising a pawl, 25 a cam rotating with an element of said machine, and means for driving said pawl therefrom, the said cam having active segments separated by dwells or idle segments, whereby the pattern surface may be 30 advanced or held idle during predetermined angular movements of a rotary part of said machine, and means operated by said primary pattern surface for holding said pawl out of contact with its ratchet.

In testimony whereof, I have signed my name to this specification in the presence of two subscribing witnesses.

ROBERT W. SCOTT.
